UNITED STATES PATENT OFFICE.

JOSEPH B. ACKER, OF NEW YORK, N. Y.

REGENERATIVE GAS-FURNACE.

No. 921,332.

Specification of Letters Patent.

Patented May 11, 1909.

Application filed September 22, 1908. Serial No. 454,151.

To all whom it may concern:

Be it known that I, JOSEPH B. ACKER, a citizen of the United States of America, residing in New York, in the borough of Brooklyn, county of Kings, and State of New York, have invented certain new and useful Improvements in Regenerative Gas-Furnaces, of which the following is a specification.

This invention relates to an improved regenerative gas-furnace for heating benches of gas-retorts. Heretofore gas-furnaces of this class were made of a certain depth corresponding to the length of the retorts, two furnaces being preferably built so as to abut at their inner ends and fired at their outer ends by means of two separate fires.

The object of this invention is to construct a regenerative gas-furnace in such a manner that a bench of retorts of greater than ordinary length is used, which is heated by one fire and attended to from opposite ends in such a manner that the air for combustion both for the fuel on the grate and for heating the retorts is supplied through the induction-openings in the front and rear walls of the furnace and evenly and effectively distributed around the retorts, the opposite ends of the bench of retorts being heated by two systems of air-heating flues, one for one end and the other for the other end of the retorts; and for this purpose the invention consists of a regenerative gas-furnace comprising a bench of retorts, a single gas-generating fire-place approximately centrally below the same, a primary system of air-heating flues under the grate for facilitating the combustion of the fuel in the fireplace, two secondary systems of air-heating flues, one for heating one end-portion of the gas-retorts and the other for heating the other end-portion of the gas-retorts, located at each side of the fireplace, and a series of draft-flues for drawing the hot gases around the retorts and then in downward direction around and between the systems of secondary air-heating flues and under the system of primary air-heating flues to the chimney.

The invention consists further in a bench of gas-retorts adapted to be charged at opposite ends and provided with brace-blocks for supporting the same, and means for heating up the entire bench of retorts and the brace-blocks, as will be fully described hereinafter and finally pointed out in the claims.

In the accompanying drawings, Figure 1

represents a front-elevation and a vertical transverse section of my improved regenerative gas-furnace, arranged sidewise of each other, Fig. 2 is a vertical longitudinal section on line 2, 2, Fig. 1, Figs. 3, 4, 5 and 6 are horizontal sections drawn on different superposed planes, respectively on lines 3, 3, 4, 4, 5, 5, and 6, 6, Fig. 2, and Fig. 7 is a vertical section on line 7, 7, Fig. 1.

Similar letters of reference indicate corresponding parts throughout the several figures.

Referring to the drawings, *a* represents a gas-generating fireplace which is arranged vertically below the combustion-chamber *b*. The combustion-chamber is located above the fireplace *a* and is made wider at its middle portion and contracted at its lower and upper ends, as shown in Fig. 1. It is provided with a grate of suitable construction and an ashpit *a*¹ below the grate. A stationary ashpan *a*² is located in the ashpit, the ashes and clinkers being removed from time to time through the ashpit-door, which is located at one end of the fireplace. In the side-walls of the fireplace are arranged a number of superposed air-heating flues, while above the air-heating flues and combustion-chamber is arranged a bench of retorts *r*, which are supported on top and bottom brace-blocks *c* located below and above the retorts, said brace-blocks being connected vertically above the combustion-chamber by lateral bridge-blocks *c*¹. The lowermost retorts *r* are supported on brace-blocks *c*² which are formed of two overlapping blocks, the outer ones being inserted at their outer ends into the side-wall of the furnace and the inner ends into the recessed ends of the inner blocks *c*², which form at the same time the top-parts of the discharge-channels for the heated air delivered to the combustion-chamber from the air-heating flues. The upper brace-blocks *c* rest by their outer ends on projecting bricks in the side-walls and abut by their inner ends against the bridge-blocks *c*¹. At suitable intervals throughout their length, the retorts are surrounded by side-blocks *c*⁵ which are held in position by the brace-blocks and bridge-blocks, as shown in cross-section in Fig. 1. The retorts *r* are open at both ends and made in sections of suitable length, so that each full retort extends throughout the entire furnace to a depth of twenty feet or more. Above each

vertical set of supporting brace-blocks are arranged step-shaped blocks c^6 over which extends the arched top of the furnace. The step-shaped blocks c^6 form a counter-resistance for the bench of retorts and prevent the lifting of the top brace-blocks when the coke is pushed out of the upper set of retorts.

In the side-walls of the furnace, at each side of the fireplace a , are arranged a set of primary air-heating flues f , which are shown in Figs. 1, 4 and 7. The flues f receive the air-supply from air-openings o in the front-wall of the furnace, said air-openings being opened or closed by suitable regulating plugs p . The primary air-heating flues are divided by longitudinal partitions f^1 into two flues each, one being the inlet and the other the return flue. The inlet and return-flues are connected by a lateral channel f^2 at their inner ends, so that the air which is drawn in is heated up in the air-flues and conducted through downwardly-inclined channels or outlets f^3 that terminate below the grate of the fireplace, into the space below the grate and then in upward direction and through the burning fuel on the grate, so as to furnish a controllable quantity of air to the fuel for the generation of carbon oxid gas.

The fuel is supplied to the fireplace by a charging-opening o^1 located in one end-wall above the floor-line of the furnace and connected by a short inclined furnace-wall a^4 with the fireplace proper. An opening o^5 in the opposite end serves as a stoking-opening. Both openings o^1 , o^5 are closed by suitable doors. The stoking-opening o^5 is connected by an inclined wall a^5 with the inner end of the grate. By this arrangement the firebox can be set back sufficiently to bring it to the center of the entire furnace. A vertical wall a^6 is located below the inclined charging-portion of the fireplace and set back from the front-wall of the bench of retorts, and provided with an opening o^6 in which is placed an iron frame i having doors d for inserting the clinker-bars and loosening the clinkers so as to drop them through the grate-bars into the ashpan. The doors d for the firepit and ashpit are of the usual construction, and are cooled by water supplied by a suitable pipe, the frame i being provided with side-rests for inserting and holding iron plates, which are inserted into the fuel when removing the clinkers, and transverse bars for supporting the clinker-bars. This construction is well known and forms no part of the present invention.

Above the primary air-heating flues f , by which air is admitted to the fuel on the grate, are arranged in the side-walls of the furnace two systems of secondary air-heating flues g , g . The two systems of secondary air-heating flues are superposed one above the other and separated by the larger draft-flues h for the products of combustion that are

generated in the combustion-chamber and which, after being drawn around all the retorts and into the space below the arch of the furnace for heating up the retorts and the supporting brace-blocks of the same, are conducted in downward direction through the draft-flues h located above, between the secondary air-heating flues and between the secondary and primary air-heating flues and below the latter to the main-channel m . The draft-flues h are of larger size than the air-heating flues so as to permit the free draft of the gases of combustion through the main-channel m and the smokestack with which the same is connected. At the rear-end of the lowermost draft-flues h are arranged sliding dampers e , shown in Figs. 4 and 7, by which the draft in the flues is regulated.

The lower system of secondary air-heating flues g draws in the air through openings in the front-wall of the furnace into the inlet-portion of the flue, each flue being divided by a vertical partition g^1 into an ingoing and return channel, as shown clearly on the right-hand side of Fig. 6. The air is heated during its passage through the channels and is then conducted through short vertical channels g^2 at the front-wall of the furnace in upward direction to longitudinal channels g^3 located below the brace-blocks supporting the bench of retorts, said channels g^3 being divided about midway of their length by partition-blocks g^4 . From the longitudinal channels g^3 the heated air passes through lateral education-channels g^5 into the combustion-chamber b , where it mingles with the carbonic oxid generated in the fireplace and is burned at high heat. The burning gases are drawn around the retorts in upward, backward and downward direction and through the channels n between the retorts and the side-walls of the furnace and delivered into the upper draft-flues and from the same into the intermediate and lower draft-flues and from the latter to the main-flue and chimney. The secondary air-heating flues g located in both side-walls of the furnace are separated by the draft-flues from each other, as before mentioned. The upper set of secondary air-heating flues g receive their supply of air from openings in the front-wall of the furnace, conduct the air through the ingoing and return-channels and the vertical channel g^2 into the front-portion of the longitudinal channel g^3 and deliver the air through the front-half of the education-channels g^5 into the combustion chamber, while the lower air-heating flues serve for supplying the heated air to the rear-half of the air education-channels, one-half of the education-channels receiving its hot-air supply from openings in the front-wall and the other half from openings in the rear-wall of the furnace.

The advantages of my improved regenerative gas-furnace are, first, that the entire fur-

nace with its retorts is heated by one single large fireplace, permitting thereby the use of retorts of great depth, which can be charged, cleaned and discharged from both ends; second, that by dividing the longitudinal connecting channels between the secondary air-heating channels and the eduction-channels into two groups—a front and a rear group—and providing for each group separate secondary air-heating flues, the uniform heating of the retort-chamber and retorts by and a uniform distribution of the heated air from the combustion-chamber through the retort-chamber and around the retorts is obtained; third, that by the arrangement of the brace-blocks for supporting the retorts in connection with the bridge-blocks and abutting bricks and the stepped blocks below the arch of the furnace, a very reliable and strong support for the retorts is obtained that permits the convenient removal of worn-out retort-sections and brace-blocks and the renewal of the same by new retort-sections and brace-blocks; fourth, that by the accessibility of the gas-furnace from the front and rear the air-heating flues and draft-flues can be conveniently cleaned by the usual openings and stoppers for the same; and, fifth, that by the construction described a gas-furnace is obtained which can be operated at a considerable saving in time, labor and fuel.

Having thus described my invention, I claim as new and desire to secure by Letters Patent:

35 1. In a regenerative-furnace, the combination of a central combustion-chamber, a bench of retorts supported above the same, an upper and a lower set of air-heating flues located in each side-wall of the combustion-chamber, longitudinal connecting-channels in said side-walls and above said air-heating flues, a partition-block dividing said longitudinal connecting-channels into front and rear connecting-channels, vertical channels 40 communicating with the outer ends of said front connecting-channels and the adjacent ends of the upper air-heating channels, vertical channels communicating with the outer ends of the rear connecting-channels and the 45 rear-end of the lower air-heating flues, lateral eduction-channels in the side-walls of the combustion-chamber communicating therewith and with said front and rear connecting-channels, separate air-induction openings for 50 supplying air to each of said air-heating flues, and draft-flues passing adjacent to said connecting-channels, over said upper air-heating flues, between said upper and lower air-heating flues and under said lower air-heating flues.

2. In a regenerative-furnace, the combination of a central combustion-chamber, a bench of retorts supported above the same, a set of primary air-heating flues in the lower 55 part of the side-walls of the combustion-

chamber, sets of upper and lower secondary air-heating flues in said side-walls above said primary air-heating flues, longitudinal connecting-channels above said upper secondary air-heating flues, a partition-block dividing 60 said longitudinal connecting-channels into front and rear connecting-channels, vertical channels communicating with the outer end of said front connecting-channel and the front-end of said upper secondary air-heating flue, vertical channels communicating with the outer ends of said rear connecting-channels and the rear-ends of said secondary lower air-heating flues, lateral eduction-channels in the side-walls of the combustion- 65 chamber communicating with the combustion-chamber and with said front and rear connecting-channels, separate air-induction openings for supplying air to each of said air-heating flues, and draft-flues passing adjacent to said connecting-channels, over said upper secondary air-heating flues, between said upper and lower secondary air-heating flues, between said lower secondary air-heating flues and said primary air-heating flues 70 and under said primary air-heating flues.

3. In a regenerative gas-furnace, the combination, with a bench of retorts, of means for supporting said retorts, a single fireplace located below said bench of retorts and near 75 the center of the same, and provided with charging and stoking openings in the end-walls of the furnace.

4. In a regenerative gas-furnace, the combination, with a bench of retorts, said retorts being chargeable at both ends, of means for supporting said retorts, a single fireplace located below said bench of retorts and provided with a charging-opening in one end-wall and a stoking-opening in the other end-wall, and inclined walls extending from the charging and stoking openings in downward direction toward the grate.

5. In a regenerative gas-furnace, the combination, with a bench of retorts and means 80 for supporting the same, said retorts being chargeable at both ends, of a single fireplace extending below the bench from one end-wall of the furnace to the other, a combustion-chamber arranged at the upper part of 85 the fireplace, a charging-opening in one end-wall and a stoking-opening in the other end-wall of the furnace, a downwardly-inclined wall extending from the charging-opening to the pit of the fireplace, an inclined wall extending from the stoking-opening toward the grate, and a pit-opening for the lower portion of the fireplace.

6. In a regenerative gas-furnace, the combination of a fireplace, a combustion-chamber at its upper part, retorts chargeable at 90 both ends supported on the side-walls of the fireplace and combustion-chamber, brace-blocks for supporting the lowermost retorts, intermediate brace-blocks between the lower 95

and upper retorts, side-blocks at both sides of the retorts, bridge-blocks between the intermediate brace-blocks, and step-shaped retaining blocks interposed between the uppermost brace-blocks and the arch of the furnace.

In testimony, that I claim the foregoing as

my invention, I have signed my name in presence of two subscribing witnesses.

JOSEPH B. ACKER.
